CLAIM

The ornamental design for a medical container nest, as shown and described.

DESCRIPTION

FIG. 1 is a front and right side perspective view of my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan elevational view thereof; and,

FIG. 8 is an enlarged, partial front and right side perspective view thereof.

The broken lines in the figures show portions of the medical container nest that form no part of the claimed design.

The medical container nest is shown with one or more symbolic breaks in length. The appearance of any portion of the article between the break lines forms no part of the claimed design.

1 Claim, 6 Drawing Sheets
